UNITED STATES PATENT OFFICE.

CHARLES H. GILL, OF CHICAGO, ILLINOIS.

WASHABLE GARTER.

1,361,713.

Specification of Letters Patent.

Patented Dec. 7, 1920.

Application filed December 10, 1919. Serial No. 343,946.

To all whom it may concern:

Be it known that I, CHARLES H. GILL, a citizen of the United States, residing at Chicago, in the county of Cook and State 5 of Illinois, have invented a new and useful Washable Garter, of which the following is a specification.

My invention relates to garters of the type wherein a resilient band encircles the 10 leg below the knee and above the calf of the leg and has a part extending downwardly from said band and provided with means for gripping and holding the hose, and the objects of my invention are, first, 15 to provide a garter of such construction as to have the required or desirable resiliency to retain its place on the leg without binding the muscles and without employing the elastic webbing band ordinarily used 20 for this purpose; second, to provide a garter whereof the portions which come into contact with the skin of the leg may be made of material that may be washed without injury; third, to provide a garter having 25 resilient means, hose gripping means and fastening and adjusting means all readily removable from the garter proper or cloth portion, so that said garter proper may be separately laundered; fourth, to provide a 30 combined fastening and adjusting means for the said garter; and, fifth, to provide means whereby the said combined fastening and adjusting means and the hose gripping means are kept from coming into direct 35 contact with the skin of the user.

I attain these objects by means of the construction illustrated in the annexed drawing, in which—

Figure 1 is a perspective view of the 40 whole garter; Fig. 2 is an enlarged fragmentary plan view of a portion of the garter proper and of the fastening, adjusting and resilient means thereof; Fig. 3 is a section taken on the line 3—3 of Fig. 2; and 45 Fig. 4 is an enlarged section taken on the line 4—4 of Fig. 1.

A band 11 of flexible, washable and substantially inelastic material, such as cloth or the like, is provided with a widened portion 50 12 at one of its ends and the wide portion 12 terminates at its unconnected end in a pocket 13 formed by doubling over the end of said wide portion 12 and sewing along the doubled edges with stitches 14.

55 A plate 15 is provided with slots 16 and 17 cut through it and of such length

as to permit the band 11 to pass through them. One end of the plate 15 is adapted to fit into the pocket 13 and nearly all of the balance of the plate 15 has the widened 60 portion 12 of the band 11 behind it. The band 11 passes up through the slot 16 in the plate 15 and down through the slot 17 in the plate 15 and is adapted to continue thence around the leg of the user and to be 65 then fastened resiliently to the plate 15 by means of the compression or frictional fastener 20.

A spring 18, preferably or wire bent in a series of sharp angles or zigzags to lie 70 flat against the plate 15, is secured at and near one of its ends to the plate 15 by means of rivets 19 or other suitable fastening means, or a short section of rubber may be employed in place of spring 18. A compression 75 or frictional fastener or buckle 20 is secured to the spring 18 or the section of rubber aforesaid at its end opposite from the rivets 19. Since such fasteners or buckles are old in the art, may be of any several 80 constructions and are not claimed by me as my invention, it will be unnecessary to describe this fastener in detail in this specification.

The end of the band 11 opposite from its 85 widened end 12 is adapted to pass through this fastener or buckle 20 to a point where sufficient tension of the band 11 upon the leg is secured by drawing out the spring 18 and is then secured by the gripping of 90 the fastener or buckle 20.

A shaped part 21, of similar material to that of the band 11, is secured to the band 11 by means of stitches 22' and terminates downwardly in a narrow portion 22. The 95 free end of the narrow portion 22 is doubled over to form a pocket 30 by means of stitches 31 along its doubled edges.

A plate 23 having a widened portion 23' near its upper end has slots 24 and 25 100 through this widened portion 23'. The narrow portion 22 of the part 21 is adapted to pass outwardly through the slot 24 and to return through the slot 25 and to pass down behind the plate 23 and to receive the lower 105 end of the plate 23 in the pocket 30.

A flexible part 26, preferably of leather, is secured to the plate 23 by a hinge 27 and a hose gripping member 28, of well known construction, is hingedly connected to the 110 end of the flexible part 26 from the end that is secured to the plate 23. A button

29 is secured to the plate 23 and is adapted to coact with the hose gripping member 28.

A set of these garters consists of two each of the plates 15, with their associated attaching, fastening, adjusting and resilient means, and of the plates 23, with their attaching and hose gripping means and of four or more of the cloth or similar material parts. Thus, two of these washable 10 cloth parts may be in process of laundering while the other two are being worn.

To prepare a new or cleansed garter for use, the wide portion 12 of the cloth part is doubled over to conform to the length of 15 the slots 16 and 17 and is passed forwardly through the slot 17 and downwardly or rearwardly through the slot 16 and drawn through these slots until all of the wide portion 12 is through and enough of the main 20 portion of the band 11 to permit of inserting the end of the plate 15 in the pocket 13. The band 11 is then pulled back through the slots 16 and 17 as far as permitted by the engagement of the end of the plate 15 and 25 the pocket 13. The end of the narrow part 22 of the appendage 21 is passed from the rear through the slot 24 in the plate 23 and then back through the slot 25 and drawn through those slots far enough to permit of 30 inserting the lower end of the plate 23 in the pocket 30. The narrow part 22 is then pulled back through the slots 24 and 25 as far as permitted by the engagement of the pocket 30 with the end of the plate 23.

35 To adjust the garter upon the leg, the band 11 is passed around the leg and through the fastener or buckle 20. The band 11 is pulled through the said fastener until the spring 18 is sufficiently extended 40 to give the desired pressure against the leg to the band 11 and is then fastened in that position. Thus, the garter may be adjusted to legs of varying diameters and to varying tastes as to snugness of fit or pressure desired.

45 The hose are gripped and held between the button 29 on the plate 23 and the hose gripping member 28 in the ordinary and well known manner.

50 While I have described and illustrated a specific and preferred embodiment of my invention, it will be evident that numerous departures from the construction herein described might be made without departing 55 from the spirit of my invention. I do not, therefore, limit my claims to the specific construction shown.

I claim:

1. In a washable garter, the combination 60 of a leg band of washable, flexible and substantially inelastic material provided with a pocket at one of its ends, a plate of metal or other material adapted to have one of its ends fit into the said pocket and provided 65 with two slots near its opposite end through

which the said leg band is adapted to pass, a spring secured at one of its ends to the said plate and carrying a fastening member at its opposite end and a downwardly depending portion of said garter permanently 70 attached to said leg band and provided with a hose gripping member adapted to be attached to or detached from the said portion of said garter at will.

2. In a washable garter, the combination 75 of a leg band constructed throughout of washable, flexible and inelastic material and having no permanently secured parts or attachments of differing material, a plate adapted to be secured to or removed from 80 the said leg band at will, a resilient member having one of its ends secured to the said plate, a fastening member carried by the free end of the said resilient member, a hose supporting member permanently secured to 85 the said leg band and constructed throughout of washable, flexible and inelastic material, with no permanently secured parts or attachments of differing material, a hose gripping plate adapted to be secured to or 90 removed from the free end of the said hose supporting member at will, and a locking member secured to the said hose gripping plate and adapted to coact with the said 95 plate to secure the hose firmly to the said hose supporting member.

3. In a washable garter, the combination 100 of a leg band and a hose supporting pendant secured thereto, both being constructed throughout of washable, flexible and substantially inelastic material and having no permanently secured parts or attachments of differing material, a widened end part of the said leg band, a pocket formed in the said widened end part, a plate adapted to 105 fit partly into the said pocket and to be secured to the said widened end of the said leg band at will in such manner as to be prevented by the said leg band from contacting with the person of the user and 110 adapted to be removed from the said pocket and from the said leg band at will, a resilient member having one of its ends secured to the said plate, a narrower end of said leg band, a fastening member carried by the 115 free end of the said resilient member and adapted to secure the said narrower end of the said leg band to the said resilient member at whatever point on the said narrower end of the said leg band will bring about the 120 desired tension of the said resilient member, a second pocket formed in the free end of the said hose supporting pendant, a second plate adapted to partly fit into the said second pocket and to be secured thereto at will 125 in such manner that said second plate will be prevented from contacting with the person of the user by the said hose supporting pendant and adapted to be removed from said second pocket and from said hose sup-

130

porting pendant at will, a button carried by said second plate, and a hose gripping member hingably secured to the said second plate and adapted to engage with the button 5 to secure the hose firmly to the said hose supporting pendant.

4. In a washable garter, the combination of a garter member consisting of a leg band portion and one or more pendant portions 10 and of washable, inelastic and flexible material, pockets formed in the said leg band and pendant portions, attachable members adapted to be slipped into or out of said pockets and to be thus secured to or separated from 15 the said garter member at will, a resilient element carried by one of said attachable members, a fastening element carried by the

said resilient element, and fastening elements carried by the others of said attachable members.

20

5. In a washable garter, the combination of a washable, inelastic and wholly flexible garter member, a resilient member, fastening members, and means for wholly disassociating the said garter member from all of 25 the other said members at will.

6. In a washable garter, the combination of a cloth garter member, a resilient member, fastening members, and means for disassociating all of the other said members 30 from the said garter member at will so that the remainder of said garter member is wholly washable cloth.

CHARLES H. GILL.
